UNITED STATES PATENT OFFICE.

ANNA E. DUNBAR, OF ALBANY, NEW YORK.

DESIGN FOR A SHIRT-WAIST BELT.

SPECIFICATION forming part of Design No. 30,865, dated May 23, 1899.

Application filed March 16, 1899. Serial No. 709,340. Term of patent 7 years.

To all whom it may concern:

Be it known that I, ANNA E. DUNBAR, a citizen of the United States, residing at Albany, in the county of Albany and State of New York, have invented and produced a new and original Design for Shirt-Waist Belts, of which the following is a specification, reference being had to the accompanying drawing, forming part thereof, which drawing is a view of a shirt-waist belt, showing my new design.

As shown, the essential features of my new design consist of a belt comprising the strip-form portion A, having an outer surface of polished metallic appearance, terminating at an end thereof with buckle C, and the strap-form portion B, having its face-side surface made with a leather-like appearance, strongly contrasting with the metallic appearance of the face side of portion A, so as to produce a pleasing effect when viewed by a beholder. The portion A has its upper and lower edges a a' parallel, with its lower edge plain, and

has its plainness of body relieved by a series of perforations e e, having an ornamental outline of form as shown. The terminal buckle 25 end of said portion A of the belt is relieved of plainness by the two surfaces c c of circular form and projecting above the plane of the surface of said end of portion A of the belt. At the junction of portion B with portion A are surfaces c' c', having a circular form of outline and projected above the plane of the surface of portion B, to which these surfaces serve as ornamental figures.

Having described my invention, what I 35 claim, and desire to secure by Letters Patent, is—

The design for a shirt-waist belt, as herein shown and described.

ANNA E. DUNBAR.
